COOLING SYSTEM FOR INTERNAL COMBUSTION ENGINES

Emil Zoerlein, Dearborn, Mich., assignor to Ford Motor Company, Dearborn, Mich., a corporation of Delaware

Application January 13, 1938, Serial No. 184,784

7 Claims. (Cl. 123—178)

The object of my invention is to provide a cooling system especially adapted for internal-combustion engines when used in industrial installations. In such installations it is very desirable that the conventional radiator and fan be eliminated because the fan consumes between one and two horse power and produces considerable noise in operation. In the past installations have been provided in which the radiator and fan were eliminated, but in these installations the cooling water was conducted directly to the engine cylinder block. These units did not prove satisfactory because the cold cooling water produced cold spots in the engine which caused warpage of the engine cylinders and also produced inefficient combustion in those cylinders adjacent to the cold water inlet. It will be readily apparent that if in such installations the amount of cold water is restricted sufficiently to maintain the adjacent cylinders at an operating temperature, the cylinders further away from the inlet will overheat. It is, therefore, the purpose of my invention to provide means for introducing cooling water into the engine cooling system in such manner that it cools all of the cooling medium in the engine before the water is fed to the cylinder blocks.

A further object of my invention is to provide a cooling system as above described in which the introduction of a small amount of cold water circulates a relatively large volume of cooling water through the block, the volume of water circulated being many times that of the volume of cold water introduced into the system. In this way a large volume of warm water is forced rapidly past the heated cylinders and valve chambers to thereby prevent cold spots in any part of the motor and still adequately conduct the heat away from the motor.

Still a further object of my invention is to provide a thermostatically controlled means for regulating the flow of cold water into the cooling system to thereby maintain a uniform operating temperature for the engine under all loads.

Still a further object of my invention is to provide a motor, as above described, having a manually operated means in conjunction with a thermostatically controlled cold water inlet so that the operator may introduce cold water into the system, irrespective of the position of the thermostat. In this manner the operator may fill the cooling system while the engine is not operating. This function is necessary in connection with a thermostatically controlled water inlet because after the various hose connections

are made the system must be filled with water to initially place the engine in operation. If this is not done heat will not be conducted to the thermostat so that it will not register the temperature of the motor. The thermostat under these conditions will not open up to allow the introduction of cold water when the motor temperature rises above its normal operating temperature. With the manually operated valve shown, the system may be filled with cold water before the engine starts and then the thermostats will function to maintain the motor at a predetermined operating temperature.

With these and other objects in view, my invention consists in the arrangement, construction and combination of the various parts of my improved device, as described in this specification, claimed in my claims, and illustrated in the accompanying drawing, in which:

Figure 1 is a side elevation of a V-type eight cylinder motor having my improved cooling system installed thereon.

Figure 2 is a front elevation of the installation, shown in Figure 1, the cooling water manifold associated therewith being shown in vertical section to better illustrate the construction.

Figure 3 is a sectional view, taken upon the line 3—3 of Figure 2, and

Figure 4 is a sectional view, taken upon the line 4—4 of Figure 2.

Referring to the accompanying drawing, I have used the reference numeral 10 to indicate the cylinder block casting of a V-type eight cylinder motor. A pair of brackets 11 are bolted to the forward end of the block 10, which brackets serve both as supports for the front end of the motor and as water inlets for the respective blocks of the motor. Cylinder heads 12 are bolted over the outer ends of the cylinders in the conventional manner, each of which heads is provided with a water outlet flange 13. Cooling water is circulated through the motor in the conventional manner; that is, it enters the cylinder blocks through the inlets 11 and then circulates around the four cylinders in each block and then enters the cylinder heads 12. The water is then discharged through the outlet flanges 13. A valve chamber cover plate 14 is bolted over the upper central portion of the block 10, which plate not only encloses the valve chamber but also serves normally to support a generator and fan assembly. The generator and fan are not used in this installation but a cooling water manifold is bolted to the cover plate instead. My improved manifold is secured by a

bolt 15 to a forward vertical face on the cover plate 14.

My manifold is preferably formed as a casting which extends transversely across the top of the motor. A cold water passageway 16 extends from one end of the manifold therethrough to the center of the motor, while directly beneath the passageway 16 a distributing passageway 17 is provided which extends the length of the manifold. A warm water circulating passageway 18 extends transversely across the manifold beneath the passageway 17.

It will be noted from Figure 2 that tubes 19 extend from the respective ends of the manifold 15 downwardly to the brackets 11, the upper ends of tubes 19 communicating with the respective ends of the passageway 18 while their lower ends enter the water intake brackets 11 of the engine.

It will also be noted from Figure 1 that a hose 20 connects each outlet flange 13 with the respective ends of the passageway 18. During the normal operation of the motor the cooling water is heated in the cylinder blocks and rises through the hoses 20 and enters the passageway 18 at 25 each end thereof. The water then flows downwardly through the tubes 19 into the inlet members 11 to the cylinder blocks. In order to circulate the water in this manner I have provided an injector nozzle in each of the tubes 19. Each 30 injector comprising a Venturi sleeve 21 which is inserted in the upper end of each tube 19. A nozzle 22 extends from each end of the passageway 17 downwardly into the adjacent Venturi sleeve 21 so that when water is discharged through 35 the nozzle 22 it draws the water from the passageway 18 to thereby circulate the water through the entire cooling system.

After the water in the cooling system has reached a normal operating temperature means 40 is provided for injecting cold water through the nozzles 22. When such water is being injected an equivalent amount of water must be discharged. To take care of this I have provided an exhaust 45 passageway 23 which is cast in the manifold in position parallel to the passageway 18. The exhaust passageway 23 extends from the center of the manifold to one end thereof. An overflow pipe 24 is screwed into the outer end of the passageway 23 so as to conduct the overflow of 50 water away from the unit.

From the foregoing it will be seen that when water is being injected through the nozzles 22 hot water from both of the hoses 20 will be drawn down through the tubes 19 and mix with the cool 55 water injected. The resultant warm water will then be fed to the motor. The amount of cold water which is injected through the nozzles causes a portion of the water flowing outwardly through the hoses 20 to flow through the passageway 18 to the center thereof and then outwardly through 60 the outlet passageway 23 and outlet pipe 24. It will be noted that the water which is exhausted has reached the highest temperature in the cooling system. An extremely important feature of 65 this system is that rapid circulation of the cooling water is obtained without the use of pumps or the like.

In order to control the flow of water through the nozzles 22 to that required to efficiently cool 70 the motor, I have provided thermostatically operated valve unit which comprises a poppet valve 25 which fits into a valve seat 26. The seat 26 is formed as a tubular member which extends down through a vertical opening at the center 75 of the manifold. The valve 25 proper is disposed

between the inner end of the passageway 16 and the distributing passageway 17 so that when the valve 25 is closed, water will not flow from the inlet passageway 16 to the distributing passageway 17.

The valve 25 is directly connected to an expanding bellows 27, which bellows extends downwardly through the wall which separates the passageways 17 and 18 and is located directly in front of the entrance to the outlet passageway 10 23. Thus, the hot water in the system in exhausting through the passageway 23 must strike 15 against the bellows 27. A pocket 28 is formed at the center portion of the passageway 18 into which the bellows extends, which pocket is adapted to retain a small amount of water. Thus, even should the flow of water through the nozzles 22 be stopped a certain amount of the water flowing by thermosyphon action through the manifold 18 will mix with the water in the pocket 28 to 20 thereby expand the bellows 27 when the temperature is approaching the upper limit. This pocket is formed as a safety measure because without same the water level in the passageway 18 might be reduced to a point where the bellows would be 25 exposed to vapor instead of being immersed in the cooling fluid.

The operation of the device, after the cooling system has once been filled, is as follows:

The motor is started and the valve 25 remains 30 closed. Cooling water is therefore not permitted to enter the system. Consequently, the motor heats up quite rapidly and thus causes a definite flow of the cooling water through the tubes 19 by thermosyphon action. Hot water enters the 35 manifold and maintains same at substantially the same temperature as the cylinder heads 12. The expansion of the cooling fluid due to its increased temperature causes a small portion thereof to flow inwardly through the passageway 18 so as 40 to enter the outlet passageway 23. This flow of hot water causes the bellows 27 to expand thereby open the valve 25. As soon as the valve 25 opens water flows from the passageway 16 to the distributing passageway 17 and then to the 45 two nozzles 22 from which it is injected downwardly through the tubes 19. This increases the speed of circulation and insures cooling of even the hottest parts by the warm water entering the motor. Water will continue to flow through 50 the nozzles 22 until the warm water starts to be discharged. The warm water being twenty or thirty degrees cooler than the hot water, causes the bellows 27 to contract which closes the valve 25. In actual practice the valve 25 is not opened 55 and closed but simply is reduced in aperture until a balance is reached. When the motor is idling or doing light work the valve 25 will remain only partially open, while when the motor is operating under full load the valve 25 will be opened fully to thereby allow a proportional increase in the cooling water entering the system. Thus a uniform operating temperature for the motor is maintained regardless of work being done by the motor.

The only disadvantage inherent in the construction just described is that after the device is first assembled water cannot flow through the valve 25 to fill up the cooling system. Consequently, if the motor is started at such time it would probably burn up as there would be no medium to transfer the heat from the hot motor to the bellows 27. In order to overcome this, I have provided a manually operated valve 29 which is inserted in a lateral opening in the wall 75

that separates the passageways 16 and 17, as will be noted from Figures 2 and 3. When this valve is in the position shown, which is the normal operating position, water is not permitted to flow through this valve between the passageways. However, when the valve is open the water may flow directly from the passageway 16 through the valve to the passageway 17 to thereby fill up the cooling system independently of the thermos-
10 statically operated valve 25. After the system has once been filled the valve may be closed and it need not again be operated until some part of the system has failed.

Among the many advantages arising from the use of my improved device, it may be well to mention that warm water is forced through the engine in a relatively large amount so that the temperature difference between the inlet and outlet is quite small. This causes a more uniform 15 heat distribution throughout the engine and prevents cold spots thereby increasing the operating efficiency of the motor.

It has been mentioned that the generator which is ordinarily supported by the valve chamber cover plate 14 is omitted from this installation and the manifold installed in its place. This necessitates other means for maintaining the storage battery, used for starting, in a charged condition. To accomplish this I provide a small 20 charger which is operated from the 110-volt lighting system and connect this to the battery at all times. If desired, the battery may be dispensed with and the charger connected directly to the ignition system to operate same. This, of 25 course, requires hand cranking of the motor.

A further advantage of my invention is that ample water circulation is accomplished without water pumps or the like, thereby simplifying the construction.

Still a further advantage results in that the amount of cold water used is directly proportional to the load of the motor to thereby effect a considerable saving in cooling water.

Some changes may be made in the arrangement, construction and combination of the various parts of my improved device without departing from the spirit of my invention, and it is my intention to cover by my claims such changes as may reasonably be included within the scope 50 thereof.

I claim as my invention:

1. An internal-combustion engine having a water jacket around its combustion chambers, said water jacket having inlet and outlet openings 55 therein, comprising a conduit extending from said outlet to said inlet opening so that cooling water may circulate through said jacket and conduit, said jacket and conduit forming a cooling system, an injector nozzle disposed within said conduit, means for injecting relatively cold water through said nozzle to produce an injection action which both cools and circulates all of the fluid in said cooling system, and means for discharging heated water from 60 said water jacket in an amount equal to the cold water introduced through said nozzle, said heated water being discharged from the cooling system at a point between said outlet opening and said nozzle.
2. An internal-combustion engine having a water jacket around its combustion chambers, said water jacket having inlet and outlet openings therein, a conduit which conducts water from 65 said outlet opening back to said inlet opening,

said water jacket and conduit forming a cooling system, an injector nozzle disposed within said conduit, a cold water inlet pipe, a valve disposed between said inlet pipe and said nozzle, and a thermostat immersed in the water within said conduit at a point adjacent to the high temperature portion thereof, said thermostat opening and closing said valve so that when the cooling water adjacent thereto reaches a predetermined temperature said thermostat opens said 10 valve and allows relatively cold water to be injected through said nozzle, the injector action produced by said cold water circulating the water in the entire cooling system.

3. An internal-combustion engine having a water jacket around its combustion chambers, said water jacket having high and low temperature portions comprising, a conduit for conducting fluid from said high temperature portion to said low temperature portion, an injector nozzle disposed within said conduit, means for injecting relatively cold water through said nozzle to produce an injector action which circulates all of the water in said water jacket and conduit, and means for discharging heated water from said 20 cooling system in an amount equal to the cold water introduced through said nozzle, said discharged water being drawn from the high temperature portion of said water jacket.

4. An internal-combustion engine having a water jacket around its combustion chambers, said jacket having inlet and outlet openings therein, a conduit extending from said outlet to said inlet opening so that cooling fluid may circulate through said jacket and conduit, an injector nozzle disposed within said conduit, means for injecting relatively cold water through said nozzle to produce an injection action which circulates all of the fluid in said jacket and conduit, and means for discharging an amount of 30 heated water from said conduit equal to the amount of cold water introduced through said nozzle, said heated water being discharged from said conduit at a point between said outlet opening and said nozzle.

5. An internal-combustion engine having a water jacket around its combustion chambers, said jacket having inlet and outlet openings therein, a conduit extending from said outlet opening to said inlet opening so that water may circulate through said conduit and jacket, an injector nozzle disposed within said conduit, a cold water inlet pipe, a valve disposed between said pipe and said nozzle, and a thermostat disposed within said conduit in position between said outlet opening and said nozzle, said thermostat controlling the operation of said valve so that upon the cooling water adjacent thereto reaching a predetermined temperature said thermostat opens said valve to allow relatively cold water to be 55 injected through said nozzle, said injector action circulating the water in the entire conduit and water jacket in a direction from said nozzle towards said inlet opening.

6. An internal-combustion engine having a water jacket around its combustion chambers, said jacket having inlet and outlet openings therein, an injector manifold disposed above said motor, a conduit extending from said manifold 60 to said inlet opening, a second conduit extending from said outlet opening to said manifold, an injector nozzle disposed within said manifold, a cold water inlet pipe connected with said manifold, a valve disposed between said inlet pipe and 70

said nozzle, and a thermostat interposed within said manifold between said nozzle and the outlet opening in said water jacket, said thermostat controlling the operation of said valve so that upon the cooling water adjacent thereto reaching a predetermined temperature said thermostat will open said valve and allow relatively cold water to be injected through said nozzle, said injector action circulating the cooling fluid in said conduit from said nozzle towards the inlet opening in said water jacket.

7. An internal-combustion engine having a water jacket around each of its cylinder blocks, each of said water jackets having inlet and outlet openings therein, a cooling water distributing manifold extending across the upper part of said engine, said manifold having a cold water inlet passageway formed therein which extends the length of the manifold, a circulating water passageway extending the length of said manifold, conduits extending from the respective ends of said circulating passageway to the adjacent inlet

openings in said cooling water jackets, nozzles extending from the respective ends of said cooling water passageway into said conduits, return pipes extending from said outlet openings to the adjacent ends of said circulating water passageway, an outlet passageway in said manifold, said outlet passageway extending from the intermediate portion of said cooling water passageway, and a thermostatically operated valve for regulating the flow of water into said cooling water passageway, the temperature responsive portion of said valve being interposed at the junction of said outlet passageway and said circulating passageway so that upon the water exhausting through said outlet passageway reaching a predetermined temperature said valve will open and allow relatively cold water to flow into said cold water inlet passageway and thus be discharged through said nozzles, the injection action produced thereby circulating the water through both cylinder blocks.

EMIL ZOERLEIN.
